UNITED STATES PATENT OFFICE.

JAROSLAV STRAKA, OF CHICAGO, ILLINOIS.

TOY.

1,351,450.

Specification of Letters Patent. Patented Aug. 21, 1920.

Application filed June 19, 1919. Serial No. 305,342.

To all whom it may concern:

Be it known that I, JAROSLAV STRAKA, a citizen of the United States, residing at Chicago, in the county of Cook and State of Illinois, have invented certain new and useful Improvements in Toys, of which the following is a full, clear, and exact specification.

This invention relates to a toy, and more particularly a war toy in which a plurality of elements or figures are continuously moving.

One of the objects of this invention is to provide a toy in which the moving elements can be quickly detached, and others substituted therefor.

A further object is to provide a device adapted for use in connection with figures such as may be cut out of newspapers or books.

A further object is to provide a toy, all of the parts of which are detachably fastened in such a manner that the whole toy may be dismantled quickly.

A still further object is to provide a toy construction having one or more bodily movable elements, certain of said elements having parts that are adapted to move relative to other parts thereof.

Briefly stated, the structure illustrating the invention comprises a movable member, such as an endless belt having suitable driving means, and having detachably connected thereto a plurality of elements or figures.

These figures or elements may be of any desired nature, and in the embodiment illustrated soldiers and toy aeroplanes are shown. Certain of the figures may be made of relatively movable parts, such as rotatable aero-

plane propeller blades.

Attention is now directed to the accompanying drawings forming part of this application, in which similar characters of reference indicate corresponding parts in all the figures.

Figure 1 is a front elevation of my invention;

Fig. 2 is a top plan view showing the relative position of the aeroplanes;

Fig. 3 is a sectional view taken on the line 3-3 in Fig. 2 in the direction of the arrows;

Fig. 4 is the fragmentary plan view—partly in section—showing the driving gear and the endless belt;

Fig. 5 is a detailed sectional view showing the means for driving the aeroplanes;

Fig. 6 is a detailed sectional view showing the detachable fastenings for the aeroplane brackets or supports;

Fig. 7 shows a vertical section and front elevation on an enlarged scale of the supports carried by the endless belt, which in turn carry the clips to which the figures are attached;

Fig. 8 shows a top plan and side elevation of the construction of the supporting clips by which the different figures are carried; and,

Fig. 9 shows in top plan and elevation and side elevation the construction of the support shown in Fig. 7.

In carrying my invention into practice, I provide a base or frame 10, which is of any suitable material, preferably wood or metal, and which has slidably connected thereto 75 a casing 11 provided with a slotted portion 11', and having a platform 12 fixed thereon. The platform 12 is provided with serrations 13 (one of which is shown) at regular intervals, the purpose of which will be described later. A second casing 14 is detachably supported centrally of the platform 12 by means of the frame member 15. The member 15 has adjacent its four corners apertures 16 for the reception of shafts 17, 85 which are detachably fastened in the apertures 18 of the base 10, the shafts 17 having loosely mounted thereon adjacent their lower ends washers 21', which are supported by the base 10. The shafts also carry spools 90 19, having on their lower ends flanges 20 which rest on the washers 21'. The flanges 20 guide an endless belt 21 carried by the spools 19, the belt being of any flexible material—preferably of elastic type. One of 95 the spools 19 has fixed at the lower end thereof a gear 22, which meshes with a vertically disposed gear 23 mounted on and fixed to the crank 24 journaled in a bearing 25 carried by the base 10; the gears 22 and 23 being held properly in mesh by means of a washer 26. The crank 24 is provided for the purpose of propelling the toy, but it is understood that a spring or an electric motor may be substituted therefor if desired.

The manner in which the figures are fastened will next be described. The endless belt 21 has securely fastened at regular intervals metallic upright members 27 by means of tongues 28, as illustrated in Fig. 110 7. The member 27 is bifurcated at its upper end, and is provided with an off-set portion

29 (see Fig. 9) for the purpose of supporting a clip adapted to support a series of detachable figures. The clip 30 is detachably connected to the member 27 by means 5 of a loop 31 formed on one end of the clip. The clip 30 is preferably made of spring material, and has at regular intervals loops 32 adapted to detachably support a plurality of figures; figures such as those illustrated at 33 and 34. The figure 33 is further provided with an oscillating leg 35, pivoted to the figure at 36. It will be seen that this leg 35 is relatively longer than the other leg of the figure, and upon the forward movement of the figure the oscillating leg 35 will engage the serrations or raised portions 13 of the platform 12, and as it passes over will give the leg an oscillating movement from the full line position to the 20 dotted line position shown in Fig. 1.

The means for mounting and propelling the aeroplanes will next be described. A shaft 37 is journaled in the frame member 15 and the base member 10, and has fixed 25 adjacent its lower end a roller 38 (see Fig. 5), positioned in such a manner that it engages the endless belt 21 and is rotated by said belt. At the upper end of the shaft 37 and affixed thereto is a member 39 provided 30 with oppositely disposed apertures 40, the upper portion of said apertures being slotted, as at 41, for the purpose of preventing the rotation of the aeroplane support rods 42, which at the same time are easily 35 detachable therefrom. The aeroplane support rods 42 are preferably bent at an angle from the vertical end, and have detachably connected thereto at their upper ends a movable toy, such as the monoplane 43 and 40 the biplane 44. The members 43 and 44 have pivoted thereto propellers 45, which are freely rotated when the toy is in motion by reason of the oppositely inclined end portions 45'.

45 A brief description of the operation of the above described toy construction will now be given. When the operator desires to set the toy in motion the crank 24 is rotated, whereby the belt 21 moves around 50 the spools 19. The belt carries with it the clip 30, to which are attached the various figures 33 and 34, and as the figure 33 is moved around the toy the leg 35 will engage the serration 13 and be moved thereby. 55 The motion of the belt will also rotate the shaft 37, which in turn carries the support 39 and the aeroplane support members 42. As the shaft 37 and support rods 42 are rotated the aeroplanes will describe circles 60 about the shaft as a center, and the propeller blades will be independently rotated by the current of air formed by the movement of the planes.

From the above description and opera-

tion of my improved toy, it will be clear 65 that a simple and inexpensive construction has been designed, and a construction which can be easily and quickly assembled and taken apart. The features last noticed are important since the construction can be 70 shipped knocked down, thereby reducing the shipping space.

Although in the above specification and in the drawings I have illustrated and described certain particular forms of figures, 75 it should be understood that other types may be used if desired, and that those shown and described have been chosen merely for the purpose of practicable embodiment of the invention. Furthermore, it should be 80 understood that modification and changes may be made without departing from the spirit and scope of the invention as expressed in the following claims.

Claims:

1. In a toy comprising a frame, a movable element carried thereby, a figure mounted on said movable element and having a relatively movable member, and means carried by said frame and located in the path of said member whereby as said figure is set in motion by said movable element said member will be moved with respect to said figure. 85
2. In a toy comprising a frame, a movable element carried thereby, a figure mounted on said movable element and having a relatively movable member, said frame being provided with a raised portion located in the path of said member whereby as said figure is set in motion by said movable element said member will be moved with respect to said figure. 95
3. In a toy comprising a frame, a movable element carried thereby, a figure mounted on said movable element and having a relatively movable member pivoted thereto, and means carried by said frame and located in the path of said member whereby as said figure is set in motion by said movable element said member will be moved with respect to said figure. 105
4. In a toy comprising a frame, an endless belt, means for actuating said belt, a shaft carried by said frame and rotatably driven by said belt, and toy figures carried by said shaft and disposed in off-set relation thereto. 110
5. In a toy comprising a frame, an endless belt, means for actuating said belt, a shaft carried by said frame and rotatably driven by said belt, a plurality of supporting members carried by said shaft, and toy figures operatively connected to said supporting 115 members. 120
6. In a toy comprising a frame, an endless belt, means for actuating said belt, a shaft carried by said frame and rotatably driven by said belt, a support carried by said shaft, and a plurality of inclined supporting members detachably connected to said support and having secured thereto toy figures. 125

7. In a toy comprising a frame, an endless belt rotatably mounted thereon, supporting members fixed to said belt, and a plurality of detachable clips adapted to be attached to said supporting members.
8. In a toy comprising a frame, an endless belt rotatably mounted thereon, supporting members carried by said belt and extending upwardly therefrom, and a plurality of 10 clips each having a looped portion adapted to be detachably secured to the upper ends of said supporting members.
9. In a toy comprising a frame, an endless belt rotatably mounted thereon, supporting members carried by said belt, said supporting members having off-set portions adjacent their upper ends, and clips each having a looped portion adapted to be secured to the off-set portions of said supporting 15 members.
10. In a toy comprising a frame, an endless belt rotatably mounted thereon, supporting members carried by said belt, and clips carried by said supporting members, each of 20 said clips being provided with a plurality of laterally extending portions adapted to receive toy figures.
11. In a toy comprising a frame, an endless belt rotatably mounted thereon, supporting members carried by said belt, and clips carried by said supporting members, each of 25 said clips being provided with a plurality of laterally extending portions adapted to receive toy figures.
12. In a toy comprising a frame, an endless belt, a plurality of figures carried by said belt, means for actuating said belt and figures, a shaft mounted in said frame, a plurality of other figures carried by said shaft, and means for frictionally driving 30 said shaft by said belt.
13. In a toy comprising a frame, an endless belt, a plurality of figures carried by said belt, a shaft mounted in said frame disposed in the path of said belt, and a plurality of aeroplanes carried by said shaft operable above said figures.
14. In a collapsible toy comprising a frame, an endless belt carrying a plurality of soldiers, a shaft mounted in said frame and frictionally driven by said belt, and means for detachably fastening two oppositely disposed diverging supporting rods having aeroplane figures mounted thereon.
15. In a collapsible toy comprising a frame, an endless belt carrying a plurality of soldiers, a shaft mounted in said frame and frictionally driven by said belt, and a member fixed to said shaft provided with slotted apertures for the reception of diverging 50 supporting rods having aeroplane figures mounted thereon.

In testimony whereof I affix my signature.
JAROSLAV STRAKA.
